Primary Examiner — Kelley Donnelly(74) *Attorney, Agent, or Firm* — Jonathan M. D'Silva; MMI Intellectual Property(57) **CLAIM**

The ornamental design for a display case, as shown and described.

DESCRIPTION

FIG. 1 is a top perspective view of a display case showing my new design;

FIG. 2 is a front view thereof;

FIG. 3 is a back view thereof;

FIG. 4 is a right side elevation view thereof;

FIG. 5 is left side elevation view thereof;

FIG. 6 is a top plan view thereof; and,

FIG. 7 is a bottom plan view thereof.

The broken lines of FIG. 1 illustrate a shot glass and is included for the purposes of illustrating the environment of the design only and forms no part of the claimed design.
